GLASS SLAB FOR THE CONSTRUCTION OF
WALLS AND ILLUMINATED COVERSAldo Favaron, Milan, Italy, assignor to the firm
"Fidenza" Società Anonima Vetraria, Milan,
ItalyApplication June 28, 1938, Serial No. 216,405
In Italy January 19, 1938

7 Claims. (Cl. 72—42)

It has already been proposed to use glass slabs or blocks for the construction of walls and illuminated covers, wherein these slabs are connected together by joints of reinforced concrete. The slabs in question are generally formed by two shallow dished members assembled together by putty or the like to form closed hollow bodies. For the formation of the joints the slabs are located at a considerable distance apart and the intervening space filled with cement and reinforcing bars.

Walls and covers formed in this manner require a very large quantity of glass as also the sides as well as the front and back faces of the blocks are formed of glass and this increases the cost of manufacture and the difficulties of jointing as it is necessary to space the slabs exactly.

The invention has for its subject a novel construction of slabs of this type of which the jointing becomes very simple and which enables a considerable economy in glass to be effected as these slabs are formed of two plates of glass having end ridges forming a suitable recess for receiving lateral connecting bands of card-board, fibre, Celluloid or the like material forming the sides of the hollow slabs or blocks, said end ridges also forming projections adapted to constitute joint cavities bounded on both sides by two contiguous bands of the pliant material forming the sides of the blocks or slabs.

Two forms of construction in accordance with the invention are shown by way of example in the accompanying drawing, wherein:

Figure 1 shows at the upper portion a front view of a translucent wall, and in the lower portion, a plan view of a translucent cover.

Figure 2 is a section on the line A—B of Figure 1.

Figure 3 is a similar view on the line C—D of Figure 1.

In the construction shown, the slabs or blocks are each formed by two glass plates 1, 2 of which the ends have marginal internal recesses in which are secured, by means of putty or the like, bands 3, 4 of a pliable material, such as card-board, fibre, Celluloid, in such a manner as to form a closed hollow block, from which marginal end ridges 5 and 6 project laterally.

In the form shown at the top of Figures 1 and 2 which can be employed for the construction of a wall, the two glass plates 1, 2 are identical with one another, and the cement forming the joints between the blocks is run from the top between the two contiguous slabs of which the end

ridges nearly come into contact. The recesses in which the pliant bands are secured, form between each block a cavity to be occupied by the cement 7 which may be reinforced with iron members.

In the construction shown in the lower portion of Figures 1 and 2 and in Figure 3, which can be used for forming transparent covers, the two plates 1 and 2 are of different thicknesses, as the upper plate 2 must be capable of supporting loads. The lower plate, on the contrary, is provided with end ridges 8, 8' which are longer than the ridges 9, 9' of the upper plate 2, so that when two contiguous plates are placed side by side a free opening is left at the top through which the cement for the joint can be run.

It will be seen clearly that the construction of walls and covers with the use of slabs or blocks according to the invention can be effected very easily as the shape and dimensions of the end ridges of the glass plates automatically fix the distance between the slabs and the thickness of the joints. There is effected a considerable economy in the amount of glass which is necessary as the sides of the slabs are formed of a cheaper material.

It will be understood that the shape, size and joint recesses of the glass plates may be varied without departing from the scope of the invention.

What I claim is:

1. A glass slab or block for the construction of translucent walls and covers, comprising a pair of glass plates having internal marginal recesses and arranged to form the front and back faces of the slab, non-vitreous plates engaged in said recesses and disposed between said glass plates to form therewith a closed hollow block or slab of which said non-vitreous plates form the sides, and marginal ridges on said glass plates extending beyond said sides in such a manner that the marginal ridges and non-vitreous sides of adjacent slabs or blocks constitute a cement receiving joint space.

2. A glass slab or block for the construction of translucent walls and covers, comprising a pair of glass plates having internal marginal recesses and arranged to form the front and back faces of the slab, flexible non-vitreous plates engaged in said recesses and disposed between said glass plates to form therewith a closed hollow block or slab of which said non-vitreous plates form the sides, and marginal ridges on said glass plates extending beyond said sides in such a manner that the marginal ridges and non-vitreous sides

of adjacent slabs or blocks constitute a cement receiving joint.

3. Slab according to claim 1, wherein the glass plates are of identical form.

5 4. A glass slab or block for the construction of translucent walls and covers, comprising a pair of glass plates having internal marginal recesses and arranged to form the front and back faces of the slab, non-vitreous plates engaged in said recesses and disposed between said glass plates to form therewith a closed hollow block or slab of which said non-vitreous plates form the sides, and marginal ridges on said glass plates extending beyond said sides, and in which one glass plate is thicker than the other glass plate and the latter has its marginal ridges longer than those of the first-mentioned plate, whereby when the longer marginal ridges of adjacent slabs touch one another there is formed a joint space which is 10 open at the side of the shorter marginal ridges,

15 and is bounded at the sides by said non-vitreous plates.

5 5. A wall structure of slabs according to claim 1, having adjacent slabs arranged with their marginal ridges in approximately abutting relationship and the joint spaces filled with cementing material.

6. A weight sustaining cover structure formed of slabs according to claim 4, disposed with the thicker glass plates of the slabs on the weight 10 sustaining side of the cover and the joint spaces between the slabs filled with cementing and reinforcing material.

15 7. A weight sustaining cover structure formed of slabs according to claim 4, disposed with the thicker glass plates of the slabs on the weight sustaining side of the cover and the joint spaces between the slabs filled with cementing and reinforcing material.
